US0D1075437S

(12) **United States Design Patent** (10) **Patent No.:** **US D1,075,437 S**
(45) **Date of Patent:** **** May 20, 2025**

(54) **SPOON**

(71) Applicant: **Sabert Corporation**, Sayreville, NJ (US)

(72) Inventor: **Yohanan Siskindovich**, Florham Park, NJ (US)

(73) Assignee: **Sabert Corporation**, Sayreville, NJ (US)

(**) Term: **15 Years**

(21) Appl. No.: **29/904,477**

(22) Filed: **Oct. 6, 2023**

(51) **LOC (15) Cl.** **07-03**

(52) **U.S. Cl.**

USPC **D7/653**

(58) **Field of Classification Search**

(57) **CLAIM**

The ornamental design for a spoon as shown and described.

DESCRIPTION

FIG. 1 is top right perspective view of a spoon according to my design;

FIG. 2 is a top plan view thereof;

FIG. 3 is a bottom plan view thereof;

FIG. 4 is a right-side view;

FIG. 5 is a left-side view;

FIG. 6 is a front view;

FIG. 7 is a back view;

FIG. 8 is a cross section along the line 8-8 of FIG. 2; and,

FIG. 9 is a cross section along the line 9-9 of FIG. 2.

1 Claim, 4 Drawing Sheets
